OTHER PUBLICATIONS

U.S. Appl. No. 61/664,383, David W. Tipton et al., "Sterilization Cassette Systems, Instrument Retention Systems for Use with a Sterilization Cassette, and Configurable Instrument Retention Members for Use Therewith", filed Jun. 26, 2012.

Primary Examiner — Anhdao Doan

(74) *Attorney, Agent, or Firm* — Marshall, Gerstein & Borun LLP

(57) **CLAIM**

The ornamental design for sterilization cassette, as shown and described.

DESCRIPTION

FIG. 1 is a perspective view of a sterilization cassette in accordance with a first embodiment of the present invention; FIG. 2 is a front elevational view of the sterilization cassette illustrated in FIG. 1;

FIG. 3 is a rear elevational view of the sterilization cassette illustrated in FIG. 1;

FIG. 4 is a right side elevational view of the sterilization cassette illustrated in FIG. 1;

FIG. 5 is a left side elevational view of the sterilization cassette illustrated in FIG. 1;

FIG. 6 is a top plan view of the sterilization cassette illustrated in FIG. 1;

FIG. 7 is a bottom plan view of the sterilization cassette illustrated in FIG. 1;

FIG. 8 is a perspective view of a sterilization cassette in accordance with a second embodiment of the present invention;

FIG. 9 is a front elevational view of the sterilization cassette illustrated in FIG. 8;

FIG. 10 is a rear elevational view of the sterilization cassette illustrated in FIG. 8;

FIG. 11 is a right side elevational view of the sterilization cassette illustrated in FIG. 8;

FIG. 12 is a left side elevational view of the sterilization cassette illustrated in FIG. 8;

FIG. 13 is a top plan view of the sterilization cassette illustrated in FIG. 8; and,

FIG. 14 is a bottom plan view of the sterilization cassette illustrated in FIG. 8.

The broken lines in the drawing views illustrate unclaimed portions of the sterilization cassette and form no part of the claimed design.
